ABSTRACT: Supports are provided for holding the corners of containers transported on railway flatcars. Each support rests on the deck of the car and has pins on the bottom adapted to be anchored in a pair of perforated strips at a required position. The support includes a clamping device which extends through a slot in the deck between the perforated strips. The clamping device is movable by a handle toward the underside of the deck to lock the support to the deck. When not in use, the supports are stowable below the deck.

ADJUSTABLE CONTAINER SUPPORT MEANS FOR A RAILWAY FLAT CAR

BACKGROUND OF THE INVENTION

Container supports for railway flat cars are preferably adjustable and stowable, as set forth in U.S. Pat. No. 3,391,654, over the subject matter of which this application presents improvements. The improvements consist principally in providing means for positively locking the support to the deck of the car, and means for obtaining a finer adjustment of the positioning of the support.

SUMMARY OF THE INVENTION

A pair of perforated strips extends along each side of the deck of a flat car. A support for the corner of a container is movable along the perforated strips. The support includes a pedestal resting on the perforated strips and having a seat for the corner of a container. The pedestal has a ramp in the form of an inclined slot beneath the seat intersected by a vertical medial slot. A clamping device includes a first plate in the vertical slot, extending through a slot in the deck, a transverse plate at the top of the first plate and located in the inclined slot, and transverse members at the bottom of the first plate, below the deck. A lever having a handle connects the clamping device to the pedestal to raise the clamping device until its transverse members engage the underside of the deck. The bottom of the pedestal has dowel pins which enter the perforated strips to prevent movement of the support.

BRIEF DESCRIPTION OF THE DRAWING

The invention will be fully understood from the following description and the accompanying drawing, wherein:

FIG. 1 is a plan view partly in section.

FIG. 2 is an end view of FIG. 1.

FIG. 3 is a plan view of the pedestal.

FIG. 4 and 5 are front and rear views of the pedestal.

FIG. 6 is a plan view of the clamping device.

FIG. 7 is an end view of the clamping device.

FIG. 8 is a partial top view of the deck of a railway flat car.

DESCRIPTION OF THE PREFERRED EMBODIMENT

Referring to the drawing, the illustrated invention relates to the mounting of containers, which may be of various sizes, on the deck 10 of a railway car. At each side of the deck a pair of regularly perforated strips 12, 13 are affixed, and between them the deck has a slot 14. The deck also has openings 16, 18 for stowing container supports 20.

Each support includes a pedestal 22, a clamping device 24, and a lever mechanism or bell crank 26 including a handle 28. The pedestal has a horizontal seat 30 and adjoining walls 32 and 34 forming a trihedral corner for seating one corner of a container. The lower portion of the pedestal has an inclined slot having portions 35, 36. The lower part of the pedestal is bifurcated to form a wide vertical slot 38 of generally triangular shape. Holes 39 and 40 are provided for a pivot pin 42. Rear wall 34 has a groove 43 for receiving handle 28, and extends beyond the rest of the pedestal to provide a pair of flanges 44, 45, for holding support 20 when it is stowed in openings 16 or 18. In the bottom of the pedestal there are a plurality of holes 46, 47 for receiving dowels 48, 49.

Clamping device 24 includes a generally triangular plate 50, on the sloping side 52 of which is welded a wide flat plate 54. At its ends, plate 50 has transverse members or feet 56, 58, and in its upper corner it has a slot 60 for pivot pin 62. Plate 54 rides in the inclined slot or ramp 35, 36 of the pedestal, and is pivoted thereto by the bell crank 26 at the lower end of han-

dle 28. It can be seen that raising handle 28 pulls clamping device 24 rearwardly and plate 54, therefore, rides up ramp 35, 36 and raises clamping device 24 until transverse members 56, 58 are adjacent deck 10. The support is then locked to the deck. Dowel pins 48 and 49 in perforations 64, 65 of perforated strips 12, 13 prevent support 20 from shifting longitudinally or laterally. Latching means 66, 68-lock handle 28 in its clamping position, and when support 20 is stowed.

Dowel holes 46, 47 are spaced a shorter distance than perforations 64, 65 in order to provide a vernier relation between them. For example, if perforations 64, 65 are spaced 2 inches apart, holes 46 and 47 may be spaced 1 and one-half inches. By selecting the perforations and inserting dowel pins 48, 49 in the optimum ones of the three holes 46, 47, support 20 can be placed within one-half inch of a desired position.

When it is desired to stow away supports 20, in order to haul cargo other than containers, support 20 is moved along slot 14 to opening 16 or 18 and turned downwardly into the opening. Flanges 44, 45 then engage the deck and substantially cover opening 16 or 18, in practically the same manner as do the flanges of the container supports in aforementioned U.S. Pat. No. 3,391,654.

The foregoing description and the drawing illustrate the principles of the invention in a simple manner. It will be apparent to those skilled in the art that many variations or embellishments thereof can be made.

I claim:

1. A corner support for a container adapted to be mounted on the deck of a railroad flat car, comprising a pedestal and a clamping device connected to said pedestal and movable relative thereto, said pedestal having a seat for receiving a corner of the container and a base beneath the seat for supporting the pedestal on the deck, said base having an upwardly inclined slot therein, said clamping device including a member having a first portion in said slot and slidably therealong and a second portion extending from said first portion downwardly through said base and through a slot in the deck, said second portion having a laterally offset portion below the deck, said clamping device including manually operable means for moving said member upwardly along the inclined slot of said base for elevating said laterally offset portion substantially to the underside of the deck and retaining said member in its uppermost position for holding the support on the deck.

2. Apparatus according to claim 1, wherein said slot is T-shaped and said second portion of said member is a vertical triangular plate, and said first portion in said inclined slot is an inclined plate integral with said triangular plate.

3. Apparatus according to claim 1, wherein said clamping device includes a bell crank pivotally connecting said member to the pedestal.

4. Apparatus according to claim 3, including means for locking said bell crank when said member is in its uppermost position.

5. Apparatus according to claim 1, wherein the base of said pedestal has a T-shaped slot extending over the length of the pedestal, said T-shaped slot including said inclined slot and a slot extending downwardly from the inclined slot throughout the length thereof, said first and second portions of said member forming a T-shaped portion located in said T-shaped slot.

6. Apparatus according to claim 1, wherein the deck has a linear series of perforations longitudinally thereof and a dowel projecting downwardly from the bottom of the pedestal for entry into one of the perforations.

7. Apparatus according to claim 6, wherein said dowel is adjustable to different longitudinal positions of the pedestal having a vernier relation to the series of perforations.
